VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

WOVEN CARRIER.

1,273,790.

Specification of Letters Patent.

Patented July 23, 1918.

Application filed November 6, 1917. Serial No. 200,530.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The present invention has relation more particularly to carriers for the use of engineers, draftsmen, and others making frequent use of pencils and other articles and instruments employed in taking notes, jotting down measurements, etc., and in drafting, as well as other like work. It is a branch of the generic invention which is described and claimed in my application filed June 24, 1916, Serial No. 105,673, consisting 15 20 25 30 35 40 45 50 55 60 65 70 75 80 85 90 95 100 105

in a carrier of woven material comprising a flexible backing, and elongated pockets or loops of such material at the surface of said backing, adapted to contain pencils, etc., and having a plurality of stiffening strips combined with the said backing and paralleling the pockets or loops.

One object of the generic invention just mentioned is to produce thoroughly practical and superior carriers adapted for the use aforesaid. Another is to produce a carrier which, with its pockets or loops filled with pencils, eraser, alidade, or other articles, may be rolled transversely upon itself into approximately a cylinder of comparatively small diameter, and carried in a pocket of the user's clothing. Another is to produce a carrier capable of being rolled upon itself transversely in the manner just referred to, and stiffened lengthwise so that the pockets or loops are held from buckling or bending, and so as to reduce the liability to breakage of pencils, etc., through bending of the wearer's body.

I have carried the generic invention into practical effect by two main methods, producing thereby woven carriers of two specific types of construction, constituting two species of the genus. The application filed June 24, 1916, shows and describes a carrier of one 50 of the said types of construction, or species, produced according to one of the said main methods. The present invention consists in a carrier of the second type, or species, pro-

duced according to the other of such methods.

Carriers of the species of my application of June 24, 1916 are woven in one integral structure by special procedure in weaving. Carriers of the second species, constituting the present invention, embody a principle of construction which involves the combination of a pocket-section, comprising a body-web woven with the required longitudinal pockets or loops, and stiffening strips paralleling the said longitudinal pockets or loops, with a flexible backing constituted by a separate web of cloth upon which the said pocket-section is mounted. The said backing is made with an extension or flange which also is a feature of my generic invention, adapted to be engaged by means for connecting the carrier to a place of support, usually a garment worn by the user of the carrier. The principle of construction in question has various advantages in practice; it facilitates and expedites the manufacture of the carriers, and lessens the cost thereof.

The present invention includes other special features which are described herein and are set forth in the claims.

The drawings show an illustrated embodiment of the invention.

Figure 1 of the drawings is a front elevation of an engineer's pencil carrier constituting the said illustrative embodiment.

Figs. 2 and 3 are views in section on line 2, 2, and 3, 3, respectively, of Fig. 1, with the pocket-contents omitted.

The carrier shown in the drawings is a so-called engineer's pencil case, designed for convenient attachment to a garment worn by the user, and contrived to hold or carry conveniently for handy use certain of the articles which frequently are called into service by him. The articles provided for in this instance are five pencils *a*, *a*, etc., a pencil eraser, and a so-called alidade *d*. For the reception of the pencils the carrier is furnished with the elongated pencil loops *c*, *c*, etc. For the reception of the pencil eraser, the carrier is furnished with a short pocket *b*, which is shaped and proportioned suitably to receive an oblong block strip of eraser material. A cover-flap *e* is shown in connection with eraser pocket *b*, said cover-flap being attached by one end to the carrier ad-

5 jacent the top of the back of such pocket, and being furnished with suitable fastenings, one member of which is shown at e' , for keeping it closed in place. For the reception 10 of the alidade, the carrier is furnished with a long pocket f somewhat greater in capacity than one of the pencil loops. The eraser pocket and alidade pocket are proportioned and formed to fit the eraser and 15 alidade snugly and hold them securely by friction. The different pockets and loops are arranged side by side and parallel with one another.

In different instances in practice the number, 20 form, and arrangement of pockets and loops may vary, and they may be contrived to receive additional or different articles.

The pockets or loops are woven in integral connection with a body-web g . At 25 h is the separately prepared backing upon which the pocketed body-web is mounted. Fig. 2 shows at i , i , the strips of flexible stiffening material. In this instance the said strips occupy sheaths in the body-web 30 behind the pockets or loops and parallel with the latter. They are formed within the substance of the body-web in the weaving of the latter. The strips i , i , are slipped longitudinally into the said sheaths. The said strips 35 may be composed of various materials, but usually what is known as walohn, it consisting of steel strips coated with rubber, is employed by preference, it being convenient to procure strips of such material having a very satisfactory degree of comparative stiffness combined with flexibility, resiliency and toughness.

The sheaths usually are closed at their lower ends in the weaving, openings being 40 formed at their upper ends to admit the stiffening strips. The eraser pocket b and alidade pocket f are woven with their bottom ends closed. The pencil loops are woven open at both ends, but with their lower ends 45 contracted or constricted so as to be practically closed. The lower portions of the pencil loops are in this instance occupied by long sleeve-like metal cups, one of which is partly shown at j in Fig. 1, in which view 50 the material inclosing such cup is broken away. These cups receive the inserted pointed ends of the pencils occupying the pencil loops, and protect the pencil points.

The body-web g is woven with a narrow 55 flange g' projecting downward below the lower ends of the pencil loops, and with a narrow flange g^2 projecting upward above the upper ends of the pockets and loops. The side-margins g^3 , g^3 , of the body-web 60 project laterally beyond the end pencil loops.

The flexible backing h consists in this instance of a strip of woven material of a width suitable for the backing, that is to 65 say, a little wider than the series of pockets

and loops, and equal to the width of the body-web of the pocket section, this strip being folded upon itself twice, namely at h' and at h^2 , producing thereby three thicknesses h^3 , h^4 , h^5 , of material. The intermediate thickness, h^4 , lies upon the front face of the thickness h^3 , and the third thickness, h^5 , lies upon the front face of the said intermediate thickness. The fold at h' constitutes a smooth, turned, bottom end for the 70 backing. This end projects below the lower end of the pocket-section. The fold at h^2 is above the upper end of the pocket-section, but below the top end of the thickness h^3 . The three thicknesses h^3 , h^4 , h^5 , above the 75 upper end of the pocket-section give body and substance to the upper portion of the backing, above the pocket-section, with a smooth, turned, top fold at h^2 . The lower end of thickness h^5 is covered by the upper 80 portion of the pocket-section. The pocket-section is fastened to the backing by means of a transverse line of applied fastenings at m engaging with the flange g' at the lower end of the pocket-section, other transverse 85 lines at m' , m' , engaging with the flange g^2 at the upper end of the pocket-section, and vertical lines m^3 , m^3 , engaging with the laterally-projecting side-margins g^3 , g^3 , of the pocket-section. The various lines of 90 fastenings preferably are stitches. They serve to fasten together the different thicknesses of the backing. A transverse line m^4 of fastenings (stitches) adjacent fold h^2 holds the said thicknesses together at such 95 place.

Preferably the side-margins and top of the carrier are bound by means of a covering-strip or binding tape o which incloses the side and top edges of the backing, and 100 also covers and incloses the laterally-projecting portions of the body-web at opposite sides of the pockets or loops, the said binding-tape o being secured in place by means of the lines of stitches m^3 , m^3 , which 105 are continued around the top end of the backing.

The extensions or flanges which are constituted by the portions of the backing 110 above the fold h^2 , and below the body-web and its pockets or loops, are shown as furnished with eyelets p , p , through the holes of which may be passed the pointed portions of safety pins r , r , used in attaching the carrier to a garment of the user. The said 115 extensions or flanges are sufficiently thin and flexible to enable them to be bent or doubled transversely, more or less, so as to facilitate the application of the pins to the eyelets and the engagement of the pins with the 120 coat or shirt of the user of the carrier. The reduction in thickness of the top end of the backing by locating the fold h^2 below the eyelets renders the top extension or flange 125 thinner and more flexible than the bottom

one. As in my application filed June 24, 1916, one or more supplemental eyelets applied to the top end of the backing may be occupied by a cord or cords for connecting 5 the alidade and eraser, or other articles, flexibly with the carrier, for instance the cord *t* shown connected to the said top end and to the alidade *d*.

When the carrier with its pockets filled 10 with tubes, pencils, eraser, and alidade has been rolled upon itself transversely it forms approximately a cylinder of comparatively small diameter which may be carried in one of the user's pockets. The stiffening strips 15 keep the carrier straight lengthwise within the length of the pockets or loops so that the latter are held from buckling or bending, while the triple thickness of the backing above the pockets or loops stiffens the same 20 so that it tends to remain straight and flat, so that no difficulty is experienced in inserting the pencils, eraser, and alidade into their respective pockets or loops. The stiffening means constitutes a reinforcement 25 which reduces the liability of bending of the wearer's body to occasion breakage of pencils. If deemed advisable, one or more additional layers of cloth or other suitable material for stiffening and other purposes 30 may be introduced between the two portions of the backing.

In producing the body-web and integral pockets or loops by weaving, the top and bottom edges of the body-web are selvage 35 edges, and the sheaths, pockets or loops are produced transversely of the carrier-web. A connected sequence of carrier sections is produced by continuations of the weaving operations, they being separated after the 40 conclusion of the said operations by cutting transversely across the portions of web which connect them together in a longitudinal series. Usually, the warp-threads of the loop and pocket ply are simply floated be- 45 tween one series of pockets or loops and the next, without interweaving with webs of filling, and after the carrier sections have been separated from one another by cutting across the intermediate portions of body- 50 webs on transverse lines the loose ends of floated warp-threads projecting at the sides of the first and last pencil loops are trimmed away.

What is claimed as the invention is:—

55 1. A carrier of woven material comprising a flexible body-web having elongated pockets or loops woven upon one surface of said body-web, and a flexible backing upon which the said body-web is mount- 60 ed with the side-margins of the body-web and those of the backing secured together by applied fastenings, said backing having an extension or flange above said body-web adapted to be engaged by means for con- 65 necting the carrier to a place of support.

2. A carrier of woven material comprising a flexible body-web having elongated pockets or loops woven upon one surface of said body-web, a plurality of stiffening strips paralleling said pockets or loops, and a flexible backing upon which the said body-web is mounted with the side-margins of the body-web and those of the backing secured together by applied fastenings, said backing having an extension or flange above said 70 body-web adapted to be engaged by means for connecting the carrier to a place of support. 75

3. A carrier of woven material comprising a flexible body-web, elongated pockets or loops woven upon one surface of said body-web, a plurality of sheaths woven in said body-web paralleling said pockets or loops, and a plurality of stiffening strips contained within said sheaths, combined with a 80 separately-formed flexible backing to which the margins of the body-web are attached by applied fastenings, the said backing having an extension or flange adapted to be engaged by means for connecting the carrier 85 to a place of support. 90

4. A carrier of woven material comprising a flexible body-web, elongated pockets or loops woven upon one surface of said body-web, a plurality of sheaths woven in said 95 body-web paralleling said pockets or loops, and a plurality of stiffening strips contained within said sheaths, combined with a separately-formed flexible backing to which the margins of the body-web are attached by applied fastenings, the said backing having an extension or flange adapted to be 100 engaged by means for connecting the carrier to a garment of the user of the carrier. 105

5. A carrier of woven material comprising a flexible body-web, elongated pockets or loops woven upon one surface of said body-web, and a plurality of stiffening strips paralleling said pockets or loops combined with a separately-formed flexible backing to which the said body-web is attached by applied fastenings, said backing consisting of a strip of material doubled upon itself to produce a smooth turned bottom end for the 110 carrier, with its two upwardly-extending portions secured together, the said backing having an upward extension above the body-web adapted to be engaged by means for fastening the carrier to a garment of the user. 115

6. A carrier of woven material comprising a flexible body-web, elongated pockets or loops woven upon one surface of said body-web, a plurality of sheaths woven in said 125 body-web paralleling said pockets or loops, a plurality of stiffening strips contained within said sheaths, combined with a separately-formed flexible backing to which the said body-web is attached by applied fasten- 130

ings, said backing consisting of a strip of material doubled upon itself to produce a smooth turned bottom end for the carrier, with its two upwardly-extending portions 5 secured together, the said backing having an upward extension above the body-web adapted to be engaged by means for fastening the carrier to a garment of the user.

7. A carrier of woven material comprising a flexible body-web, elongated pockets or 10 loops woven upon one surface of said body-web, and a plurality of stiffening strips paralleling said pockets or loops, combined with a separately-formed flexible backing to 15 which the said body-web is attached by applied fastenings, said backing consisting of a strip of material doubled upon itself to produce a smooth turned bottom end for the carrier, with its two upwardly-extending portions 20 secured together, the said backing having an upward extension above the body-web adapted to be engaged by means for fastening the carrier to a garment of the user.

25 8. A carrier of woven material comprising

ing a flexible body-web, elongated pockets or loops woven upon one surface of said body-web, a plurality of sheaths woven in said body-web paralleling said pockets or loops, a plurality of stiffening strips contained 30 within said sheaths combined with a separately-formed flexible backing to which the said body-web is attached by applied fastenings, said backing consisting of a strip of material doubled upon itself to produce a 35 smooth turned bottom end for the carrier, with its two upwardly-extending portions secured together, the said backing having an upward extension above the body-web adapted to be engaged by means for fastening the 40 carrier to a garment of the user, and a binding-strip finishing-off the upright side-edges and top-edge of the flexible backing.

In testimony whereof I affix my signature in presence of two witnesses.

VICTOR H. JENNINGS.
